AUTOMOBILE GRILLE GUARD

Harold Poncher and Jerry E. Poncher, Chicago,
Ill., assignors to Erie Manufacturing Co., Inc.,
Chicago, Ill., a corporation of Illinois

Application January 3, 1949, Serial No. 2

Term of patent 7 years

(Cl. D14—6)

To all whom it may concern:

Be it known that we, Harold Poncher and Jerry E. Poncher, citizens of the United States, residing at Chicago, in the county of Cook and State of Illinois, have invented a new, original, and ornamental Design for Automobile Grille Guard, of which the following is a specification, reference being had to the accompanying drawing, forming a part thereof, in which—

Figure 1 is a plan view of an automobile grille guard, showing our new design;

Figure 2 is a side elevation of the same;

Figure 3 is a front elevation of said guard;

Figures 4 and 5 are, respectively, cross-sectional views taken on the planes indicated by the lines 4—4 and 5—5 of Figure 3; and

Figure 6 is a similar cross-sectional view on the line 6—6 of Figure 2.

We claim:

The ornamental design for an automobile grille guard, substantially as shown.

HAROLD PONCHER.
JERRY E. PONCHER.
